UNITED STATES PATENT OFFICE.

GUSTAV BOCKAU, OF OTTUMWA, IOWA, ASSIGNOR TO OTTUMWA IRON WORKS, OF OTTUMWA, IOWA, A CORPORATION OF IOWA.

JIGGING CONVEYER.

Application filed March 22, 1928. Serial No. 263,631.

This invention relates to rollers for jigging conveyers and has for its object broadly the provision of a construction which will insure the accurate action of the pans or units in the conveying action.

Jigging conveyers are ordinarily constructed of units which reciprocate back and forth carrying the material forward in the motion in one direction and returning in reciprocation without corresponding return movement of such material. An example of such jigging conveyer movement is found in the type of devices wherein the pans or units are advanced slowly and evenly, the material traveling with them by the friction between the material and units and the units returned suddenly and sharply and at a speed which overcomes the friction due to the momentum of the material leaving it advanced an amount substantially that of the forward movement of the pans or units. The material is conveyed thus with a step by step action.

It is desirable that the rollers upon which the pans or units are mounted during this movement remain accurately in registration with tracks both upon the pans or units and upon the ground or other fixed support. Accurate registration is desirable both laterally of the pans themselves and lengthwise in the direction of the conveying movement. Prior to my invention tedious and extended adjustment between the parts of the conveyer when it is arranged for operation has been necessary and my invention contemplates the provision of a construction greatly minimizing such adjustment.

An important object of the invention, in addition to the diminution of required adjustment, is the provision of a construction insuring greater accuracy in the conveying action.

Numerous other objects and advantages of the invention will be apparent as the invention is better understood from the following description, which, taken in connection with the accompanying drawings, discloses a preferred embodiment thereof.

Referring to the drawings,

Figure 1 is a schematic elevation of a jigging conveyer showing the same arranged for operation in a coal or other mine;

Fig. 2 is an enlarged transverse section through one of the pans and showing the roller and track construction in elevation;

Fig. 3 is a partial side elevation of the structure shown in Fig. 2.

For the purpose of illustrating my present invention I have shown in Fig. 1 of the drawings a part of a jigging conveyer comprising a plurality of jigging pans 11 connected together in suitable or usual fashion at their adjacent ends as indicated by reference characters 12. The conveyer pans thus connected constitute an extended conveyer which is reciprocated upon rollers 14 by suitable power mechanism diagrammatically indicated at 15. The rollers 14 are mounted upon cross-shafts 16 and engage upper tracks 17 secured to the pan and lower tracks 18 arranged upon the mine floor 19.

Referring now to Fig. 3, it will be noted that the tracks 18 consist or may consist of short sections each built up of longitudinal angle irons 21 and cross end angles 22. A short section is arranged beneath each roller 14 and it will be understood that the back and forth movement of the roller occurs throughout a short path of travel.

Each of the pans is of sheet metal construction having a base 23, upwardly inclined side walls 24 and downwardly extending edge flanges 25. The tracks 17 are preferably of angle iron construction and are preferably arranged to extend up into the space between the inclined pan wall 24 and the vertical flange 25, one flange 26 of such angle iron being arranged in contact with the flange 25 and secured to it at intervals as indicated at 27 by spot welding or otherwise.

The track member 17 is illustrated as arranged at an angle to the pan but this arrangement is no part of my present invention.

I provide a plurality of teeth 31 upon the periphery of each roller 14 and arrange corresponding openings or apertures 32 in the horizontal flange 33 of the track angle iron 21. Companion openings 34 are provided in the horizontal flange 35 of each track angle 17 secured to the pan.

These teeth in entering into the openings 32 and 34 maintain the registry of the rollers and both sets of track transversely of the pans and insure accurate, even reciprocating movement of the pans in the conveying action. It will be readily apparent that the construction described precludes the necessity for any preliminary adjustment, rendering the

entire apparatus self-adjusting within limits, and insures also against disarrangement of the parts in service which will require readjustment.

5 It is thought that the invention and many of its attendant advantages will be understood from the foregoing without further description, and it will be apparent that various changes may be made in the construction, and arrangement of the parts without departing from the spirit and scope of the invention or sacrificing all of its material advantages, the form hereinbefore described being merely a preferred embodiment thereof.

10 15 I claim:

1. In a jiggling conveyer, the combination of a pan along which it is intended to pass the material, stationary tracks adjacent thereto, rollers supporting said pan from said track and oscillating as an incident to said conveyer, said rollers and said track having interlocking parts preventing lateral movement of said rollers on said tracks.

2. In a jiggling conveyer, the combination 20 25 of a pan along which material is to be conveyed in the jiggling action, tracks carried by said pan and tracks arranged in fixed rela-

tion therebeneath, rollers engaging the tracks of the pan and said stationary tracks, said rollers and tracks having interlocking parts 30 preventing lateral relative movement therebetween.

3. In a jiggling conveyer, the combination of a pan along which material is to be conveyed in the jiggling action, tracks carried by 35 said pan and tracks arranged in fixed relation therebeneath, rollers engaging the tracks of the pan and said stationary tracks, said rollers and tracks having interlocking parts 40 insuring predetermined movement between said rollers and tracks in the direction of the conveying movement.

4. In a jiggling conveyer, the combination of a pan along which material is to be conveyed in the jiggling action, tracks carried 45 by said pan and tracks arranged in fixed relation therebeneath, rollers engaging the tracks of the pan and said stationary tracks, said rollers having protruding teeth upon their 50 rolling faces and said tracks being provided with openings for the receiving of said teeth in the rolling action.

GUSTAV BOCKAU.
